GARMENT

Loretta Novy, St. Louis, Mo., assignor to Weil-Kalter Manufacturing Company, St. Louis, Mo., a corporation of Missouri

Application November 26, 1942, Serial No. 466,998

1 Claim. (Cl. 2—73)

This invention relates to improvements in women's garments, and more particularly to an undergarment referred to as a slip.

An object of the invention is to provide a woman's slip that may be readily drawn on or off over the head of the wearer and, by inherent construction, snugly fit the waist and bust when worn.

Another object of the invention is to provide a woman's slip having a front panel of material cut on the straight, with bust panels cut on the bias in order to cause circumferential stretch, and a back panel cut on the bias, thus providing a slip in which there is no shortening of the longitudinal dimension of the slip when the wearer is seated, and yet will provide sufficient stretch both in the bust section and in the skirt section to permit the garment to snugly fit the contour of the wearer.

Another object of the invention is to provide a garment of the class mentioned, which is simple in construction, and yet which will accomplish the objects recited.

Additional objects will be apparent from the following detailed description of the invention, taken in conjunction with the accompanying drawing, in which:

Fig. 1 is a front view of the garment;
Fig. 2 is a rear view;

Fig. 3 is a section on the line 3—3 of Fig. 1;

Fig. 4 is a section on the line 4—4 of Fig. 2;
and,

Fig. 5 is a section on the line 5—5 of Fig. 2.

The garment includes a front panel 1 that forms the front of the skirt and extends circumferentially to the rear section of the garment forming the front and the sides 2 of the skirt. The material of this section is cut on the straight, as indicated in the drawing, so that there is little or no circumferential stretch in this section.

The skirt is completed by a back panel 3, formed as is particularly illustrated in Fig. 2, in which it will be noted that the panel extends across the back of the waist and while cut vertically on the edges, curves to the natural figure when worn.

This panel is cut on the bias and, therefore, affords to the garment the ability to stretch circumferentially and adjust closely to the wearer's body. Since the front and side of the skirt have practically no circumferential stretch, when the wearer of the garment is seated, there is no tendency of the skirt to pull up at the front. The shortening of the vertical dimension of the skirt, due to the circumferential stretching, comes at the back, so that a seated wearer has that portion of the skirt that shortens vertically concealed. This feature is of considerable advantage, and constitutes an important improve-

ment over garments in which the front and sides of the skirt are formed on the bias, because such garments appreciably shorten in vertical dimension and pull the skirt upwardly, and in many cases over the knees of the wearer.

The bust section of the garment is formed from breast panels 4, that extend around the side of the bust section, where they are seamed to back panels 5, and the back panels are connected by a central seam, as illustrated in Fig. 2. The material for the bust panel 4, and the back panel 5 is cut on the bias, so that when the garment is put on or taken off over the head of the wearer, there will be a circumferential stretch around the bust and waist sections, and when worn the circumferential retraction will cause the section to hug closely the contour of the body of the wearer.

It will be noted by reference to Fig. 1, that the front panel is formed with a V-shaped extension 6 that flares outwardly at the bottom and the bust panels are seamed thereto, and by reference to Fig. 3, it will be noted that the bust panels are made of a double thickness of material, thereby affording extra support for the bust. The back panels 5 are connected at the waist line to the central section by a row of stitching curved downward to middle back.

What is claimed is:

In a slip or like garment, a skirt portion and an upper portion, comprising a front skirt panel having a lower edge, lateral edges and an upper edge, the panel being narrower at its upper part than at its lower part, and having a width to extend around the sides of the garment into the rear thereof, to dispose its lateral edges at the rear of the garment, the upper edge of the front skirt panel extending at least as high as the waist of the garment, and at its front middle portion extending upwardly above the waist toward the top of the garment and converging into substantially a point, the front panel being cut on the straight at its middle front part, a rear skirt panel cut on the bias, said rear skirt panel having lateral edges joined to the lateral edges of the front skirt panel, and an upper edge extending upwardly at least as high as the waist of the garment, a pair of rear upper sections joined together at the middle of the back and each extending laterally from the junction, and disposed on the bias, the said rear upper panels being secured at their bottom edges to the upper edge of the skirt portion, and having outer lateral edges extending upwardly therefrom, a pair of breast panels cut on the bias, each breast panel being secured to the outer lateral edge of a corresponding rear upper panel, and to the upper edge of the front panel including the converging portion thereof.

LORETTA NOVY.
